[57] CLAIM

The ornamental design for a tray for bakery products, substantially as shown and described.

DESCRIPTION

FIG. 1 is a top plan view of a tray for bakery products showing my new design;

FIG. 2 is an elevational view with the tray standing on its side, the opposite side being the same in appearance; and

FIG. 3 is a view looking from the top of FIG. 2, the opposite side being the same in appearance.
